UNITED STATES PATENT OFFICE.

FREDERICK F. SCHMITT, OF PHILADELPHIA, PENNSYLVANIA.

MATTRESS.

1,420,450.

Specification of Letters Patent. Patented June 20, 1922.

Application filed March 5, 1921. Serial No. 449,705.

To all whom it may concern:

Be it known that I, FREDERICK F. SCHMITT, a citizen of the United States, residing at Philadelphia, in the county of Philadelphia

5 and State of Pennsylvania, have invented certain new and useful Improvements in Mattresses, of which the following is a specification.

One object of my present invention is to 10 provide an improved mattress with a novel form of backing sheet for the top and bottom and which can be used with advantage in a mattress embodying the principles of construction as covered in my United States 15 Patent, No. 1,014,261; my improved backing sheets serving as means for retaining in shape the sides and ends of the mattress case and the plaited and tufted portions of the 20 top and bottom during the time when the mattress is being made and when it is being used.

Another object of my invention is to make my improved mattress of a durable and comparatively simple construction and so that it 25 can be readily manufactured.

These objects, and other advantageous ends which will be described hereinafter, I attain in the following manner, reference being had to the accompanying drawings in 30 which—

Figure 1 is a top plan view of a mattress including my present invention.

Figure 2 is an enlarged section taken on the line 2—2 of Figure 1; a portion of the 35 length being broken away; the filling being omitted in one part.

Figure 3 is an enlarged section taken on the line 3—3 of Figure 1; a portion of the length being broken away.

40 Figure 4 is a perspective view illustrating my improved backing sheet positioned relatively to the top or bottom of the mattress.

Figure 5 is a perspective view of one of my improved backing sheets.

45 Figure 6 is a fragmentary enlarged plan view as it appears when looking from the inside of the mattress with the filling omitted,

Figure 7 is a view of similar character to 50 Figure 6 looking from the outside of the mattress before the tufting takes place,

Figure 8 is a fragmentary enlarged section showing more clearly the arrangement of the plait with respect to the backing sheet and 55 illustrating the same at a larger scale than that shown in Figure 2, and

Figure 9 is a perspective view of similar character to that shown in Figure 4 illustrating a slightly modified arrangement of my invention.

60

Referring to the drawings and particularly to Figures 1 to 8 inclusive, my improved mattress includes a case 10 which is preferably made of the relative sizes as covered in my above mentioned United

65 States patent. For example the case 10 includes end portions 11, sides 12, top 13 and bottom 14 which are preferably made of flexible cloth; the ends and sides being sewed together and being of dimensions of

70 the finished mattress while the top 13 and bottom 14 includes cloth of larger dimensions than the dimensions prescribed by the ends 11 and sides 12. I form plaits 15 and 16 in the end and side edges of the top and

75 bottom; the plaits being in line with the rows of tufts. Directly adjacent the inner surfaces of the top 13 and bottom 14, I position backing sheets 17 which, in the present embodiment of my invention as illustrated, consist of sheets of cloth having holes or openings 18 arranged in the present instance in rows extending longitudinally and transversely. Thus there are portions 19 between the openings 18 which extend longitudinally

80 and other portions 20 between the openings which extend transversely. These backing sheets may be secured to the top and bottom by rows of stitching 21 which extend longitudinally through the portions 19 and rows

85 22 of said stitching which extends transversely through the portions 20 of the backing sheets. The outer edges of the sheets 17 are preferably included in the seam 23 which secures the ends and sides to the top and

90 bottom. The stitching 21 extends substantially at right angles to the plaits 16 while the stitching 22 extends substantially at right angles to the plaits 15. The plaits 15 and 16 may be arranged to extend

95 100 over the openings 18 so that the excess material 24, which is produced by making the plaits in the top and bottom which are of larger dimensions than the sides and ends,

105 can be drawn inwardly through the openings 18 and tufted as shown in Figures 1, 2 and 3; said tufts being indicated at 25.

By thus arranging the backing sheets with respect to the top and bottom, it will be noted that the crossed and rectangular arrangement of the portions 19 and 20 will hold the top and bottom in their tufted posi-

110

tion with the plaits in their proper form and alignment; said longitudinal and transversely extending portions 19 and 20 also serving to take up strain on the top and bottom in which the strain will be resisted in common planes since the sheets 17 have the portions 19 and 20 in the same plane. It will be noted that the backing sheets thus formed can be sewed in position on the inner surfaces of the top and bottom prior to joining the top and bottom to the sides and ends and due to this arrangement the top and bottom can be easily handled during manufacture of the mattress since the backing sheets will hold the plaits in their proper position and will also keep the excess tufting portions 24 in position so that when the filling 26 has been inserted between the backing sheets, it is an easy matter to quickly form the tufts since all of the parts are retained in their proper aligned positions to permit the insertion and tying of the tufting members 27.

In Figure 9, I have illustrated the form of my invention which is substantially similar to that above described with the exception that the backing sheets, such as the backing sheet 17^a as shown, which are placed directly adjacent the top and bottom are only secured to the case 10 at the seams 23. In all other respects the construction and arrangement of parts would be the same as that described in connection with Figures 1 to 8 inclusive and I have therefore given corresponding parts similar reference characters.

While I have described my invention as taking a particular form, it will be understood that the various parts of my inven-

tion may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A mattress including sides and ends forming a frame having the outer dimensions of the finished mattress; a backing sheet of the length and breadth of the finished mattress with its edges secured to the frame; spaced openings in the backing sheet, and a cover of greater dimensions than the finished mattress adapted to be drawn into the openings in the backing sheet by the tufting stitches.

2. A mattress including sides and ends forming a frame having the outer dimensions of the finished mattress; a backing sheet of the length and breadth of the finished mattress with its edges secured to the frame; spaced openings in the backing sheet, and a cover of greater dimensions than the finished mattress, the cover being plaited at the ends and sides in line with the tufts and adapted to be drawn into the openings in the backing sheet by the tufting stitches.

In testimony whereof I have signed my name to this specification in the presence of two subscribing witnesses.

FREDERICK F. SCHMITT.
